[57] **CLAIM**

The ornamental design for a pair of truck body side panels, as shown and described.

DESCRIPTION

FIG. 1 is a perspective view showing the first truck body side panel of a pair of truck body side panels showing our new design;

FIG. 2 is a elevational view of the right side of the first truck body side panel of FIG. 1, the right side view of the second side panel being a mirror image thereof;

FIG. 3 is a elevational view of the left side of the second truck body side panel, the left side view of the first side panel being a mirror image thereof;

FIG. 4 is a section view taken along line 4—4 of FIG. 2; FIG. 5 is a section view taken along line 5—5 of FIG. 2; FIG. 6 is a top plan view, taken along line 6—6 of FIG. 3, a top plan view of the panel of FIG. 2 being a mirror image thereof; and,

FIG. 7 is a bottom plan view, taken along line 7—7 of FIG. 3, a bottom plan view of the panel of FIG. 3 being a mirror image thereof.

The broken lines shown in all drawing views are for illustrative purposes only and form no part of the claimed.

1 Claim, 5 Drawing Sheets
